Attorney

UNITED STATES PATENT OFFICE.

JOHN TORRENT, OF MUSKEGON, MICHIGAN.

ELECTRIC LAMP.

Application filed January 17, 1925. Serial No. 3,118.

To all whom it may concern:

Be it known that I, JOHN TORRENT, a citizen of the United States, residing at Muskegon, in the county of Muskegon and State of Michigan, have invented a new and useful Electric Lamp, of which the following is a specification.

This invention relates to electric lamps and aims to provide a lamp having a filament of a novel construction whereby the life of the lamp may be greatly increased.

A further object of the invention is to provide a lamp having a double filament, the construction of the filament being such that when one of the wires of the filament becomes broken or burned out, the adjacent wire of the filament may be brought into operation and the lamp again used.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view of an electric lamp constructed in accordance with the invention.

Figure 2 is a fragmental sectional view illustrating one of the wires of the filament of the lamp as in circuit with the central contact screw of the lamp.

Figure 3 is a fragmental sectional view illustrating the central contact screw as in circuit with the opposite wire of the filament of the lamp.

Referring to the drawing in detail, the reference character 5 indicates the bulb of the lamp which is fitted in the threaded base, in the usual and well known manner.

The base 6 includes the insulating sections 7 and 8, the section 8 being secured by means of the central contact screw 9 form-

ing a part of the lamp. Secured to the section 7 is a contact member 10 to which the wire 11 of the filament is connected, the upper portion of the wire 11 being connected with the central wire 12 of the filament, which in turn extends through the base 6 as at 13, in order that it may make connection with the usual lamp socket.

The reference character 14 indicates a supporting block which is secured to the member 7 by means of the screw 15 which screw also secures the contact plate 16 to the supporting block 14 and as shown, this plate 16 extends beyond one wall of the supporting block 14 to be engaged by the central contact screw 9 when the section 8 has been removed as clearly shown by Figure 3 of the drawing.

The reference character 17 indicates a wire of the filament which is in circuit at its upper end with the wire 12, the lower end of the wire 17 being connected with the contact plate 16 at 18.

From the foregoing it will be obvious that should the wire 11 of the filament be rendered inoperative, the section 8 of the base may be removed and the contact screw 9 passed through the section 7 as shown by Figure 3 of the drawing, whereupon the screw will contact with the plate 16 completing the circuit through the wire 17 and central wire 12 of the filament.

I claim:

In an electric lamp, a base, a filament including a central wire and lateral wires in circuit with the central wire at one of its ends, a contact screw extending through the base, contact members in circuit with the lateral wires, said contact screw adapted to engage the contact members to complete circuits through the wires, and a removable section forming a part of the base for spacing the screw from one of the contact members.

In testimony that I claim the foregoing as my own, I have hereto affixed my signature.

JOHN TORRENT.
